UNITED STATES PATENT OFFICE.

GEORGE G. GREENBURG, OF CHICAGO, ILLINOIS.

DESIGN FOR A BADGE.

SPECIFICATION forming part of Design No. 31,617, dated October 10, 1899.

Application filed September 18, 1899. Serial No. 730,946. Term of patent 3 years.

To all whom it may concern:

Be it known that I, GEORGE G. GREENBURG, a citizen of the United States, residing at Chicago, in the county of Cook and State of Illinois, have invented and produced a new and Improved Design for Badges, of which the following is a full, clear, and exact description.

In the drawings, Figure 1 is a face view of the badge. Fig. 2 is a face view of the reverse side of the medal.

As shown in the drawings, the leading or essential feature of my design consists in having a shield arranged centrally upon one face of the medal, which is circular in its general contour and has a raised bead around its edge. The upper portion of the shield has a series of stars thereon and the lower portion is striped. Upon said striped portion of the shield a sheaf of grain is displayed. The shield is surrounded by a background of water and land. At one side of the shield a ship is displayed; at the other the figure of an Indian standing upon the shore of the land. Upon the reverse side of the medal a building is shown, as seen in Fig. 2.

The medal hereinbefore described is suspended by a ribbon, which is secured to a flag-bar at its upper end and extended through an eye in the medal. This flag-bar consists of a staff set diagonally and a banner extending laterally therefrom. The banner is shown as curved or partially folded.

Having thus described the invention, what I claim as new, and desire to obtain by Letters Patent, is—

The design for a badge substantially as herein shown and described.
